UNITED STATES PATENT OFFICE

LESLIE H. PETER AND REGINALD S. ABBOTT, OF LONDON, ENGLAND, ASSIGNEES, BY
MESNE ASSIGNMENTS, TO THE UNION SWITCH & SIGNAL COMPANY, OF SWISSVALE,
PENNSYLVANIA, A CORPORATION OF PENNSYLVANIA

ELECTRICALLY OPERATED APPARATUS FOR RAILWAY SIGNALING AND THE LIKE

Application filed February 18, 1928, Serial No. 255,469, and in Great Britain February 23, 1927.

Our invention relates to electrically operated apparatus for railway signaling and the like, and has for its object to provide improved arrangements whereby the unintentional operation of the apparatus by extraneous current may be effectively prevented.

Our invention is particularly, although not exclusively applicable to signaling systems comprising block or token instruments located at each end of a block section, the instruments being connected by a line conductor for transmitting signaling or controlling current from one instrument to the other in the well-known manner.

In such systems it is of primary importance to protect the block or signal instruments from undesired operation by extraneous current entering the line conductor due for instance to accidental contact of this conductor with an external source of current, and various arrangements have previously been proposed for protecting the system in this respect by utilizing a signal or controlling current of distinctive character and rendering the instruments responsive only to such current.

According to the present invention the current transmitted to the electrically operated apparatus to be protected is a pulsating unidirectional current, the apparatus being so constructed as to be unaffected by constant or non-pulsating unidirectional current, and may, furthermore, if desired, be of the polarized type so as to be differently affected in accordance with the direction or sign of the pulsating unidirectional current transmitted to the apparatus.

Our invention is illustrated by way of example in the accompanying drawings, Fig. 1 of which is a diagrammatic view showing the invention as applied to a pair of electrically controlled token instruments for controlling traffic through a block section of a single line railway.

Fig. 2 is a similar view somewhat simplified illustrating the effect of extraneous current entering the line conductor connecting the two token instruments.

Figs. 3 and 4 are views of modified forms of transmitting apparatus which may be em-

ployed in the system of Fig. 1, Figs. 5 and 6 are diagrammatic views showing alternative arrangements of portions of the apparatus shown in Fig. 1.

Referring now first to Fig. 1 the token instruments not shown are assumed to be located at the ends A, B of the block section. Each instrument comprises the usual arrangements for permitting the insertion and removal of tokens under the control of the electric current transmitted from one instrument to the other through a line conductor 1 and earth return 2. Each instrument is provided with arrangements for transmitting a unidirectional pulsating current to the other instrument along the line conductor 1 comprising a primary or secondary battery 3, the terminals of which are connected to the line conductor 1 through a current interrupter, a cut-out switch 6 and a reversing switch 7. The current interrupter is shown in the form of an electromagnetically operated vibrating device, for converting the direct current from the battery 3 into a unidirectional pulsating current, and comprises an electro-magnet 4 the armature 5 of which normally tends to complete a circuit from the battery 3 through the electro-magnet 4 when the switch 6 is closed. The resultant energization of the electro-magnet 4 causes the armature 5 to interrupt this circuit so that the armature 5 is alternately attracted and released. The right hand terminal of the battery 3 is thus, when the switch 6 is closed, alternately connected to

the reversing switch 7 and by setting the latter into one or other of its two operative positions a pulsating unidirectional current of normal or reverse sign or polarity is transmitted to the line conductor 1. The end of the line conductor 1 at B is connected through the primary winding 9 of a transformer 8 and a condenser 32 to the earth connection 2, the secondary winding 10 of the transformer 8 being connected through a current rectifying device 11 preferably of the copper oxide type to the terminals of a direct current relay 12. The latter, when energized by the unidirectional current supplied from the rectifier 11 is arranged to close contact 13 there-

by completing a circuit from the line conductor 1 through the energizing winding 14 of a polarized relay 15 to earth, the contacts of the relay 15 being connected to the lock magnets or other controlling devices of the token instrument at B in the usual manner.

In operation, it will be understood that the unidirectional pulsating current transmitted from A through the line conductor 1 passes through the primary winding 9 of the transformer 8 at the B end of the section and is converted into alternating current in the secondary winding 10 of the transformer. This alternating current is converted into unidirectional current in the rectifier 11 and energizes the direct current relay 12 the contact 13 of which is thereby closed to complete a circuit from the line conductor 1 through the polarized relay winding 14. It will be appreciated that since the direct current relay 12 must be energized to close the contact 13 included in the circuit of the polarized relay 15 a continuous current traversing the line wire 1 will fail to energize the direct current relay 12 owing to the presence of the transformer 8, while at the same time by suitably setting the reversing switch 7 at the A end of the section the polarized relay 15 will be caused to respond differently according to the sign or direction of the unidirectional current supplied to the line conductor 1.

It will be observed that the electro-magnet 4 of the vibrating device is included in a local circuit supplied with operating current from the battery 3 so that the current transmitted to the line conductor 1 may be relatively small, this arrangement also providing additional protection against the effect of extraneous current as will be understood from a consideration of Fig. 2.

If an earthed source X of extraneous direct current is applied to the line conductor 1 as shown in Fig. 2, the current from this source would not of itself effect the operation of the receiving apparatus owing to the presence of the transformer 8.

If, however, the source X were connected to the line conductor 1 while the transmitting apparatus indicated at A was being operated, the resulting effect would depend upon whether the current from the source X was of the same or opposite polarity to the current being supplied to the conductor from the battery 3.

In the former case, the extraneous current would obviously assist the normal current and would not have any dangerous effect upon the receiving apparatus at B although it might weaken the operation of the current interrupter.

If, however, the polarity of the extraneous current from the source X is opposite to that of the normal current supplied from the battery 3 as shown in Fig. 2 in which the direction of the normal current is shown in

full line arrows and that of the extraneous current in dotted arrows, it will be seen that the extraneous current while tending to reverse the current transmitted to the receiving apparatus at B tends to strengthen the current passing through the transmitting apparatus at A.

The energization of the electro-magnet 4 is thus increased by the pressure of the extraneous current, it being noted that the source X completes a circuit through the electro-magnet 4 and battery 3 which is not interrupted when the armature 5 is in its attracted position.

The current interrupter is so designed and adjusted that any extraneous current which might be sufficient to cause the reverse operation of the receiving apparatus at B will cause the armature 5 of the current interrupter to be held in its attracted position so that pulsating current is not supplied to the line conductor 1 from the battery 3 and the receiving apparatus at B is thus not operated.

If desired the battery 3 and current vibrator utilized as a source of unidirectional pulsating current for transmission to the line conductor 1 may be replaced by a hand or foot-operated direct current generator the commutator of which is provided with a suitable number of segments. Transmitting apparatus of this kind is illustrated in Figs. 3 and 4 in which a hand-operated generator is indicated at 16.

Referring now to Fig. 3 it will be seen that a cut-out relay 17 is provided for protection against extraneous currents, the relay 17 being provided with two windings 18, 19 and two armatures 20, 21.

The reversing switch 7 is provided with an additional contact arm 22 connected to one terminal of the relay winding 18, the other terminal of this winding being connected to the relay armature 20. A local battery 23 is provided one terminal of which is connected to the terminal 24 of the generator 16, the other terminal of the battery 23 being connected to the front contact of the relay armature 20.

The other terminal 25 of the generator 16 is connected through the relay winding 19 to the relay armature 21 the back contact of which is connected to the central contacts of the reversing switch 7. The relay armature 21 is provided with a bridging contact so that circuit leading from the relay winding 19 to the reversing switch 7 is not broken when the relay 17 is energized until after the armature 20 has come into engagement with its front contact.

The operation of the transmitting arrangements above described is as follows:

Under normal conditions the generator 16 is manually operated and supplies pulsating unidirectional current to the line conductor 130

1 through the relay winding 19, the relay armature 21 and the reversing switch 7 the setting of this switch determining the polarity of the current transmitted to the line conductor 1.

The current traversing the relay winding 19 is however insufficient to energize the relay 17 to cause the armatures 20 and 21 to be attracted.

- 10 In the event however of the current traversing the relay winding 19 becoming excessive as would be the case if a dangerous extraneous current were being applied to the line conductor 1, the armatures 20 and 21 75
15 will be moved to their attracted positions so that a local circuit through the relay winding 18 will be completed from one terminal of the battery 23 through the relay armature 20, the winding 18 and contact arm 22 to 80
20 the other terminal of the battery 23.

The upward movement of the relay armature 21 eventually interrupts the connection of the generator 16 to the line conductor after the local circuit above described has been completed and the transmission of unidirectional pulsating current to the line conductor is thus prevented so long as the relay 17 remains energized. This relay is deenergized when the reversing switch 7 is set into its inoperative position (shown in Fig. 3) owing to the interruption of the local circuit from the battery 23 at the contact arm 22.

Referring now to the modified arrangements shown in Fig. 4, the cut-out relay 17 is in this case only provided with a single winding a choke coil 26 being provided in the circuit leading from the terminal 25 of the generator 16 through the relay 17 to the reversing switch 7. The choke coil 26 is however arranged to be short circuited by the relay armature 21 so long as the relay 17 is deenergized.

Under normal conditions the generator 16 being operated, supplies unidirectional pulsating current to the line conductor 1 through the winding of the relay 17 and the armature 21, this current being insufficient to move the armature 21 from its unattracted position.

In the event however of the relay 17 becoming energized due to extraneous current in the line conductor 1 the armatures 20, 21 are attracted.

The upward movement of the armature 20 under these conditions serves to connect a condenser 27 directly across the terminals of the generator 16 while the upward movement of the armature 21 causes the choke-coil 26 to be included in the circuit from the generator 16 to the reversing switch 7. The condenser 27 and the choke-coil 26 both tend to prevent the pulsating current from the generator 16 reaching the line conductor 1 so that so long as the relay 17 is energized unidirectional pulsating current is not transmitted 65 to operate the receiving apparatus at B.

Again in a further modification the electromagnetically operated current interrupter as indicated at 4, 5 in Figs. 1 and 2 may be replaced by any other device capable of converting direct current into unidirectional pulsating current, such, for instance, as a neon tube, indicated at 28 in Fig. 5, the electrodes 29, 30 of this tube being shunted by a condenser 31. Again, in a further modification the rectifier 11 at the receiving end of the section may be dispensed with, as shown in Fig. 6, the relay 12 operated by current from the secondary winding 10 of the transformer 8 being an alternating current relay adapted when energized to close the circuit of the polarized relay winding 15 in the manner above described.

Our invention is evidently not limited to the particular arrangements and connections above described which may be varied in many respects without exceeding the scope of the invention.

Having now particularly described and ascertained the nature of our said invention and in what manner the same is to be performed, we declare that what we claim is:

1. In combination, a line conductor extending between a first and a second location, a source of energy at the first location, a transformer at the second location, a condenser at the second location; a circuit including said line conductor, said source, the primary of said transformer, and said condenser; means for periodically interrupting the current supplied to said circuit from said source, a first relay at the second location connected with the secondary of said transformer, and a second relay at the second location connected in multiple with said condenser over a front contact of said first relay.

2. In combination, a line conductor extending between a first and a second location, a source of periodically varying current at the first location having one terminal connected with ground and the other terminal connected with said conductor, a condenser at the second location having one plate connected with ground, a transformer at the second location having its primary connected between said conductor and the other plate of said condenser, a first relay at the second location connected with the secondary of said transformer, and a second relay at the second location connected in multiple with said condenser over a front contact of said first relay.

3. In combination, a line conductor extending between a first and a second location, an electromagnetically operated current interrupter at the first location, a source of unidirectional current, a reversing switch for reversibly connecting said source and said interrupter in series with ground and with said conductor, a polarized relay at the second location having one terminal connected with ground, a second relay at the second

- location, a transformer at the second location having its primary connected with said conductor and with the other terminal of said polarized relay through a front contact of said second relay, means including a rectifier for connecting said second relay with the secondary of said transformer, and a condenser connected in multiple with said contact and said polarized relay in series. 70
4. In combination, a line conductor extending between a first and a second location, a source of pulsating unidirectional current at the first location, a condenser at the second location, a transformer at the second location; 75
- 15 a circuit including said source, said conductor, said condenser, and the primary of said transformer; a first relay at the second location connected with the secondary of said transformer, a second relay at the second location connected in multiple with said condenser over a front contact of said first relay, and means at the first location for decreasing the current supplied to said circuit from said source to a value which is insufficient to energize said first relay if extraneous direct current having a value sufficient to operate said second relay is supplied to said circuit. 80
- 20 5. In combination, a line conductor extending between a first and a second location, 85
- 30 a source of pulsating unidirectional current at the first location, a condenser at the second location, a transformer at the second location; a circuit including said source, said conductor, said condenser, and the primary of said transformer; a first relay at the second location connected with the secondary of said transformer, a second relay at the second location connected in multiple with said condenser over a front contact of said first relay, and means at the first location for disconnecting said source from said conductor if dangerous 90
- 35 extraneous currents are supplied to said conductor. 95
- 35 In testimony whereof we affix our signatures.
